UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

RECEIVING TELEGRAPHIC AND TELEPHONIC IMPULSES SIMULTANEOUSLY.

No. 894,836.

Specification of Letters Patent.

Patented Aug. 4, 1908.

Application filed June 21, 1906. Serial No. 322,726.

To all whom it may concern:

Be it known that I, ISIDOR KITSEE, citizen of the United States, residing at Philadelphia, in the county of Philadelphia and State of Pennsylvania, have invented certain new and useful Improvements in Receiving Telegraphic and Telephonic Impulses Simultaneously, of which the following is a specification.

10 My invention relates to an improvement in the simultaneous receiving of telegraphic and telephonic impulses. Its object is, to provide an arrangement whereby telegraphic and telephonic impulses may be simultaneously received without interfering with each other.

15 The drawing represents in diagrammatic view my invention.

1, 1, is the line of transmission; 2 is a receiving device here shown as a polarized relay; 3, 3, are condensers; 4 is the primary and 5 is the secondary of an inductorium; and 6 the telephonic receiver. The electro-magnetic device 2 is transparent to a telegraphic impulse, but is opaque to the telephonic impulse; whereas, the condensers 3, 3, being opaque to the telegraphic impulses are transparent to the telephonic impulses. But I have found by actual experiments that an arrangement wherein only condensers are placed in shunt with the receiving device, the telegraphic impulses or rather their inductive influence greatly destroys the value of the telephonic waves. After careful tests and different arrangements, it was established by me that if the primary of an inductorium is placed in the shunt, in conjunction with the condensers and the secondary connected to the receiver, the disturbances due to the telegraphic impulses are greatly lessened and often entirely obviated, and I make use of this arrangement in simultaneously telegraphing and telephoning over lines of transmission.

It is unnecessary for me to go more in detail of this arrangement, or to point out the reasons why static means are a bar to straight currents, but not to the undulating waves of the telephonic transmitter. It suffices to say, that actual tests over lines of nearly fifty miles in length have proven the correctness of my arrangement.

In some of the tests made, I use an inducto-

rium, the secondary of which was variable, that is, the coil was divided into six sections, each section consisting of thirty ohms, so 55 that if all sections were replaced in series, the whole coil represented a value of 180 ohms, but if all were placed in multiple, the coil represented a value of only five ohms, and it was found that the best results 60 were obtained when this coil represented a very low ohmic resistance. Usually, the primary of a telephonic inductorium has a value of from one-half to three ohms and the secondary of from 50 to 80 ohms and in the 65 test in which I obtained the best results, the primary had a value of about six ohms and the secondary of about five ohms, thus reversing the order of ratio of resistance.

Having now described my invention, 70 what I claim as new and desire to secure by Letters Patent is:

1. In a line of transmission, a telegraphic receiving device inserted in series thereto, condensers shunting said receiving device, 75 in combination with an inductorium, one coil therefor connected to said condensers and forming part of the shunt around said receiving device, the other coil connected to a telephonic receiver.

2. In combination with a line of transmission, means to simultaneously receive telephonic and telegraphic impulses, said means embracing an electro-magnetic device inserted in said line, a shunt for said 85 electro-magnetic device, an inductorium in said shunt, one coil of said inductorium connected to a telephonic receiver, the second coil connected with the interposition of condensers in said shunt.

3. Means to simultaneously receive telegraphic and telephonic messages, said means embracing a telegraphic receiver inserted in series as to the line for the telegraphic messages and embracing a shunt around 95 said receiver, said shunt embracing condensers and one coil of an inductorium, a telephonic receiver, said receiver connected to the second coil of said inductorium.

4. Means to simultaneously transmit telegraphic and telephonic impulses, said means embracing for the telegraphic impulses an electro-magnetic device inserted in the line of transmission and embracing for the tele-

phonic impulses a telephonic receiver, an inductorium and condensers, the primary of the inductorium connected to the telephonic receiver, the secondary of said inductorium connected in conjunction with said condensers in shunt to said electro-magnetic device.

In testimony whereof I affix my signature in presence of two witnesses.

ISIDOR KITSEE.
